CLAIM

The ornamental design for a combined self-adhesive note pad dispenser and memo paper holder, as shown and described.

DESCRIPTION

FIG. 1 is a top, right front perspective view of a combined self-adhesive note pad dispenser and memo paper holder showing my new design;

FIG. 2 is a top plan view;

FIG. 3 is a bottom plan view;

FIG. 4 is a front elevational view;

FIG. 5 is a rear elevational view;

FIG. 6 is a left side elevational view; and

FIG. 7 is a cross-sectional view thereof, taken in the direction of arrows 1—1 in FIG. 2.

FIG. 1

FIG. 2

FIG. 3

FIG. 4

FIG. 5

FIG. 6

FIG. 7
